UNITED STATES PATENT OFFICE.

OSCAR ANDREW YOUNGREN, OF NEW YORK, N. Y.

CRUTCH, ETC., TIP.

Application filed July 29, 1921. Serial No. 438,442.

To all whom it may concern:

Be it known that I, OSCAR A. YOUNGREN, a citizen of the United States, residing at New York, in the county of New York and 5 State of New York, have invented certain new and useful Improvements in Crutches, Etc., Tips, of which the following is a specification.

In the use of crutches more or less jar is 10 imparted to the body of the user through ordinary use and considerable discomfort and oftentimes physical ills result therefrom.

The object of my said invention is to provide 15 a pneumatic tip for the lower end of the crutch of a construction which will cushion the jar and permit of inflation to any degree desired according to the weight or preference of the user, and which will serve 20 not only as a cushion to absorb the jar and strain upon the person using the crutch but will also impart more or less elasticity or spring action to the crutch; and also one that will furnish a surface which will 25 adhere when brought in contact with the pavement, floor, or ground, and prevent slipping, thus lending to the user a sense of security in the use of the crutch as well as providing means that makes its use more comfortable 30 and less injurious, all as will be hereinafter more fully described and claimed.

Referring to the accompanying drawings which are made a part hereof and on which 35 similar reference characters indicate similar parts,

Figure 1 is a side elevation of a crutch, the lower end of which is armed with one of my improved tips or pneumatic cushions, and

40 Figure 2, a central section through such pneumatic tip or cushion.

In the drawings, the parts marked A represent the crutch proper and B the tip or cushion.

45 The crutch is or may be of any appropriate form or construction and instead of a crutch, as shown, may, of course, be in the form of a cane if desired, or an artificial leg (peg leg).

50 The tip or cushion B is of bulb shape, hollow, and preferably provided with a valve 10 in one side for attachment with an air pump for the purpose of inflating the same. Said valve is of the ordinary type used in

bicycle tires, or of any appropriate type, 55 and needs no special description. It may of course be so made that inflation will not be necessary and the valve in such cases omitted.

The tip is formed with a socket 11 adapted to receive the lower end of the crutch or stick, the bottom on said socket being closed, as shown, and its upper end is surrounded by a re-enforcing bead 12. The socket is of a size adapted to fit tightly 65 around the lower end of the crutch, or rather to be expanded over the end of the crutch so as to become firmly fixed thereon. The hollow tip, including the socket, is preferably of rubber and may be readily expanded or stretched over the end of the crutch for the purpose stated. The lower part of the bulb B is preferably formed with a roughened surface 13, as shown, to adapt the same to adhere to whatever kind 75 of surface it is placed in contact with, and thus support the user against slipping and resulting accidents.

As will be understood, the bulb B may be inflated by an ordinary bicycle pump 80 through the valve 10 in the usual manner and to obtain the degree of resistance desired. Some users may desire a very hard tip and in such instance, it will be inflated to a high degree, while other users may prefer a 85 soft tip and the degree of inflation will be regulated accordingly.

Having thus fully described my said invention, what I claim as new and desire to 90 secure by Letters Patent, is:

A crutch or the like provided with a pneumatic tip consisting of a hollow substantially spherical bulb formed with a socket extending therein to receive the end of the crutch and having a horizontal wall separating the socket from the hollow portion of the tip the lower outer spherical surface of the tip being roughened, and a valve for inflating the said hollow bulb, substantially 95 as set forth.

In witness whereof, I have hereunto set my hand and seal at New York, New York this 20th day of July, A. D. nineteen hundred and twenty-one.

OSCAR ANDREW YOUNGREN. [L. S.]

Witnesses:

ANNA M. LUNDBERG,
MARION L. WALSH.
